UNITED STATES PATENT OFFICE.

WILLIAM MAIN, OF BROOKLYN, NEW YORK, ASSIGNOR TO THE RIVER AND RAIL ELECTRIC LIGHT COMPANY, OF OHIO COUNTY, WEST VIRGINIA.

FLOATING CURRENT-MOTOR.

SPECIFICATION forming part of Letters Patent No. 328,497, dated October 20, 1935.

Application filed July 25, 1885. Serial No. 172,663. (No model.)

To all whom it may concern:

Be it known that I, WILLIAM MAIN, a citizen of the United States, residing at Brooklyn, in the county of Kings and State of New York, 5 have invented a new and useful Improvement in Floating Current-Motors, of which the following is a specification, and which I designate as "Case D."

My invention relates to that form of current-motors in which the power is derived from floats attached to chains passing over sprocket-wheels, and has for its chief object to construct a power mechanism of this character which shall be capable of easy adjustment to 10 different depths of water, and which can be readily applied to ordinary scows and flat boats, not requiring, as is usually the case with current-motors, a floating support especially constructed for it.

To this end my invention consists in certain 15 details of construction, hereinafter fully described, and pointed out in the claims.

In the drawings hereto annexed and forming a part of this specification, Figure 1 is a 20 side perspective view of my improved mechanism as it appears when attached to the rear of a scow or flatboat anchored in a current of flowing water; Fig. 2 a plan view of the same. Figs. 3 and 4 are, respectively, a side elevation 25 and a plan view partly in section of the main shaft about which the swinging frame revolves and sprocket-wheels mounted thereon upon a larger scale. Fig. 5 is a plan view of a modification in which the power mechanism is mounted in a water-way which passes 30 through a double float, and Fig. 6 is a side elevation of the same.

The main shaft of the machine 1 rotates in 35 bearings 2, which bearings are parts of two iron caps terminating the longitudinal top 40 timbers of the scow. Each of these caps has an inwardly-projecting sleeve, 3, which sleeves serve as arbors for the swinging frame, the latter being designated by figures 4.

The main frame carries three sets of sprocket-wheels, the first set of two wheels, 5, 5, affording a support for the chains 6, carrying 45 the floats 7, which are pivoted to the chains at one edge by means of flat bars 8, bolted to the 50 floats and provided with eyes through which pivot 9 passes. Two other sets of sprocket-

wheels, 10 and 11, are mounted, respectively, on arbors carried by shafts connecting the triangular frames at their two remaining angles and afford further support for the chains 6.

It will be observed that the use of the sleeves 3 as arbors for the swinging frame, instead of journaling the frame directly upon the main shaft relieves the shaft of the weight and friction of the frame and permits the position of the 55 frame to be changed, as desired, without in any way interfering with the operation of the shaft.

The main shaft 1 carries a second set of two sprocket-wheels, 12, 12, through which the 60 power developed by the water-power mechanism is transmitted by means of chains or belts to pulleys on the shaft 13, journaled in bearings upon the scow. Motion-multiplying connections 14, 15, 16, 17, and 18 convey the 65 power from the shaft 13 to a dynamo, 19, or any other machinery.

A third set of sprocket or finger wheels, 20, of which two are shown in the drawings, are carried by the main shaft. These wheels have 70 a double function, first, to gradually lift the hinged floats as they pass over the sprocket-wheels 5, thus preventing the sudden drop of these blades through their whole arc of motion upon their rests 21, and relieving the 75 chain from the effects of the shock which would otherwise accompany the return of the floats to their working position. The second function of these finger-wheels is to hold the floats against their rests as they enter the water and prevent their being raised and thrown back against the chain by the eddying action of the water beneath the wheel before the float feels the force of the current upon its face. One of the fingers of the sprocket-wheels 80 20 is shown in the upper part of Fig. 3 as lifting one of the floats, and in the lower part of the same figure another of the sprocket-fingers is shown in a position to prevent the 85 backward motion of the float about entering the water.

The hinged frame is suspended at its outer end by means of a chain, 22, attached to arms 23, projecting from the hubs in which the shaft carrying sprocket-wheels 10 is journaled and 90 connected, by means of pulley-blocks and 95 ropes, with a windlass, 27, fixed to the scow.

The upper pulley-block of this hoisting mechanism is carried by the A-shaped frame 24, journaled to the deck at 25 25, and held in position by stay-rods 26. It is obvious that 5 by turning the windlass a proper degree of immersion may be given to the frame, and the power mechanism be thus adapted as desired to different depths of water.

I have shown in Figs. 5 and 6 a modified 10 form substantially similar to that heretofore described, except that the power mechanism is in this case mounted between the parts of a double float instead of to the rear of a single float. The operation of the various parts being in other respects precisely the same as that 15 already described, further explanation is unnecessary. A float of the form shown in this modification would be more expensive to construct than the form previously described, 20 but would possess the advantages of enabling a simpler form of hoisting apparatus to be used, as indicated in the figure, and of affording a water-way for the power mechanism into which the current could be turned, if desired, by deflecting surfaces.

While I have shown my swinging frame as triangular in form, it is obvious that this particular shape is not an essential feature of my invention, since other forms of frames having, 30 for instance, four or more angles, might be used, if desired.

I claim—

1. The combination, with the main shaft of a power mechanism, of journals for said shaft, 35 sleeves formed on said journals, and a frame carrying the apparatus by which the main shaft is driven arbored on said sleeves.

2. The combination of endless chains carrying floats, shafts carrying sprocket-wheels 40 for said chains, fixed journals for one of said shafts, a frame carrying the other shafts and arbored on projections from said journals, means for suspending, raising, and lowering the free end of said frame, and connecting 45 mechanism through which the power of the shaft moving in fixed journals is applied to the driven mechanism.

3. In a water-power mechanism, the combination of a floating support, a shaft journaled thereon, frames journaled concentrically with 50 but independently of said shaft, sprocket-wheels mounted on said frames, endless chains carrying floats supported by said sprocket-wheels, and means for raising and lowering the free ends of said frames, substantially as 55 described and shown.

4. The combination, with a scow or flat-boat of which the main top timbers project beyond one end, of metal caps for said timbers, a shaft journaled in said caps, and a water-power 60 mechanism pivoted concentrically with said shaft and geared thereto, substantially as described and shown.

5. The combination, with a boat or scow of which the main upper longitudinal timbers 65 extend beyond one end, of metal caps for said timbers, a shaft journaled in said caps, frames arbored on sleeves projecting from said caps, sprocket-wheels mounted in said frames, and chains carrying floats supported by the sprocket-wheels, substantially as described and shown.

6. The combination of frames of the shape of right-angled triangles carrying sprocket-wheels arbored at the angles thereof, said 75 frames being placed with their shorter sides in and perpendicular to the surface of the water, with endless chains carrying floats supported by the wheels, substantially as described and shown.

7. The combination, with a scow or other float of frames of the shape of a right-angled triangle and pivoted at their smallest angles to the scow, of sprocket-wheels arbored in said 85 frames and endless chains carrying floats supported by the wheels, substantially as described and shown.

In testimony whereof I subscribe my name in the presence of two witnesses.

WILLIAM MAIN.
